Des. 206,468
Patented Dec. 13, 1966

206,468

MEMORANDA SPINDLE

Arnold Neustadter, 1185 Park Ave., New York, N.Y.,
and Hildaur L. Neilsen, 2 Juniper St., Metuchen, N.J.
08840

Filed Aug. 12, 1965, Ser. No. 86,551

Term of patent 14 years

(Cl. D74—2)

FIG. 1 is a front and side perspective view of a memoranda spindle showing our new design;
FIG. 2 is a rear elevational view; and
FIG. 3 is a top plan view thereof.
We claim:

The ornamental design for a memoranda spindle, as shown.
